UNITED STATES PATENT OFFICE.

SALI SIMON, OF NEW YORK, N. Y.

DESIGN FOR SHELF-PAPER.

Specification forming part of Design No. 6,767, dated July 8, 1873; application filed June 16, 1873.

B.

To all whom it may concern:

Be it known that I, SALI SIMON, of the city, county, and State of New York, have invented a new Design for Shelf-Paper, used to ornament the edges of shelves, of which the following is a specification:

The nature of my design is fully represented in the accompanying drawing, to which reference is made.

The design is delineated on the paper by a series of adjacent perforations. It consists of a figure having four pointed extremities, *a a* and *b b*, two of which, *a a*, are further apart than the other two, *b b*, and impart to the figure an elongated appearance. From these

pairs of pointed extremities *a b* there extend curved lines toward the other pair, and the junction of these curved lines forms points on the inner line of the figure. The contour of the figure thus presents a varied succession of curved lines. In the center of the figure is a star, S. The scalloping forms no part of the design.

What I claim as my invention is—

The design for shelf-paper, substantially as shown and described.

SALI SIMON.
